United States Patent Office.

JOSEPH C. HOAGLAND, OF FORT WAYNE, INDIANA.

Design No. 2,967, dated March 31, 1868.

DESIGN FOR A TRADE-MARK.

The Schedule referred to in these Letters Patent and making part of the same.

TO ALL WHOM IT MAY CONCERN:

Be it known that I, JOSEPH C. HOAGLAND, of Fort Wayne, Allen county, Indiana, have originated and designed a Cut or Design for a Trade-Mark, of which the following is a full, clear, and exact description, reference being had to the accompanying specimens, making part of this specification.

The said design represents a servant presenting to a queen a plate of well-raised biscuits or cakes, the queen sitting, and being in an attitude of exclamation. Drapery represented in the background. The upper right and left-hand corners of the design each bear an ornament. Across the design, and above the figures of servant and queen, is represented, in *alto-relievo*, a scroll, bearing the words "Royal Baking-Powder."

What I claim as my invention, and desire to secure by Letters Patent, is—

The design for a trade-mark, herein set forth, and shown in the drawings.
